UNITED STATES PATENT OFFICE.

SIMON LAKE, OF BRIDGEPORT, CONNECTICUT.

SUBMARINE BOAT.

SPECIFICATION forming part of Letters Patent No. 717,101, dated December 30, 1902.

Application filed May 28, 1901. Renewed January 27, 1902. Serial No. 91,410. (No model.)

To all whom it may concern:

Be it known that I, SIMON LAKE, a citizen of the United States, and a resident of Bridgeport, in the county of Fairfield and State of Connecticut, have invented certain new and useful Improvements in Submarine or Semi-submergeable Boats, of which the following is a specification.

In order to avoid the betrayal of its presence to an enemy, it is extremely desirable that a submarine torpedo-boat should travel toward the same for an attack wholly submerged, so as to be entirely invisible from the surface until it has approached to within 15 striking distance of the hostile surface vessel and has discharged its torpedo toward the same at such close range as to insure the destruction of the enemy before discovery. Owing, however, to the present imperfect development of the mariner's compass to insure its high efficiency in submarine boats and the limited range of vision beneath the surface, the effective employment of this class of vessels for offensive purposes has up to the present time seemed at least problematical, if not wholly impracticable, as even when partially submerged with only the top of the conning-tower exposed such a boat offers a target for the small guns of a hostile war vessel.

It is the design of the present improvement to materially reduce and to render practically unnecessary the exposure of a perceptible object above the hull of a partially-submerged vessel of this type, while yet retaining the important advantage of maintaining a lookout-point above the surface for an occupant of the boat from which to view the enemy to be intercepted and attacked.

To this end the invention comprises a transparent dome or observation chamber or compartment located upon the top of the hull, external thereto and connected with the interior of the boat, for receiving the head of a lookout, whose head only need be visible above the surface of the water, the hull being wholly submerged.

The invention also includes a trap-door seated upon a suitable packing and means for flooding the inspection-dome with water when beneath the surface to prevent its collapse under an excessive external water-pressure, as well as to destroy the buoyancy and

cause the boat, with its superposed conning-tower and inspection-dome, to settle beneath the surface.

It further includes a normally open check-valve for admitting atmospheric air to the boat while the inspection-dome is above the surface, but adapted to close automatically when submerged.

It also includes a mirror attached to the inner or under face of the trap-door, whereby the latter is rendered practically invisible when in upright or open position during the normal operation of the inspection-dome.

The invention embraces certain additional features of construction, which will be hereinafter described, and pointed out in the claims annexed.

In the accompanying drawings, Figure 1 is an elevation of a submarine torpedo-boat embodying my present improvement with the upper portion of the conning-tower and the superposed inspection-dome or lookout-chamber in section to expose their construction and manner of operation. Fig. 2 is a similar partial sectional elevation of the conning-tower and inspection-dome upon a larger scale. Fig. 3 is a plan, and Fig. 4 a sectional elevation, upon a still larger scale, of the inspection-dome.

The boat is constructed with a hull *a*, a portion of which is divided into a series of water-ballast compartments *a'* (indicated in dotted lines only in Fig. 1) and is surmounted by a conning-tower *b*, having the superposed transparent inspection-dome *c*, formed of glass or other transparent substance or material. This dome is preferably of the general form indicated in the drawings, of substantially flattened oval shape, with upwardly-flaring sides

connected by slightly-rounded corners with the arched roof or top, the curvature of such corners being shown, however, as considerably exaggerated. The arched roof or crown of this dome or chamber is illustrated as arranged in angular relation to the upwardly-flaring side walls and of substantially greater curvature, but may be obviously of flat or concave form, if desired. The side walls terminate at the bottom in the lateral flange *c'*, fitted to the top of the conning-tower and secured thereto by means of the cleats *c*². The top of the conning-tower *b* is provided with a

doorway d , communicating with the observation-dome c , and which is closed when required, as in Figs. 2 and 4, by means of an upwardly-opening hinged trap-door d' , closing upon a packing e in the door-frame and having a mirror d^2 attached to its inner or under face.

The boat is shown in Fig. 1 floating at the 10 cruising water-line No. 1; but when a hostile vessel is sighted in the distance the water-ballast compartments a' are filled sufficiently to lower the hull and conning-tower wholly beneath the surface and to sink the vessel to the water-line No. 2, at which the inspection-dome only is exposed above the surface, the 15 vessel being adapted to dive at a moment's warning upon discovery without admitting water through the top of the conning-tower by reason of the superposed transparent dome 20 covering its top door. It will be observed that owing to the angle of the external walls of the dome c an observer from a surface vessel can neither see the body of the projecting dome nor can perceive the reflection of light 25 therefrom, which would be invariably reflected downwardly into the water. Also the mirror upon the upwardly-inclined open door d' will hide such door and similarly reflect downwardly any rays of light from distant 30 points at or above the surface of the water. It will therefore be seen that the only object exposed above the surface from the boat which is likely to be seen by those upon the deck of another distant vessel is the head of 35 the lookout which would be perceptible only at a distance of a few rods therefrom, and therefore be practically invisible even with the aid of a spy-glass at any point beyond striking distance for the torpedo apparatus 40 carried by the submarine boat.

To adapt the boat to be navigated effectively between the surface and the water-bed, it is desirable that the weight of the boat with its contents when submerged be only a trifle 45 greater than that of the volume of water which it displaces. In the maneuvers of a submarine boat in actual warfare and in the presence of a hostile vessel or vessels it will be found practically impossible to adjust these 50 relative weights with the nicety required, and I have therefore designed the observation-dome of such dimensions that when filled with water it shall hardly more than destroy the buoyancy of the boat when adjusted to 55 the water-line No. 2 by means of the water-ballast tanks a' . In order to provide for the filling and emptying of the dome c , the top of the conning-tower is provided with a water-pipe f , leading from the bottom of the dome 60 c outwardly to the exterior of the same and provided with a valve f' , by means of which it may be opened and closed when desired. An air-supply pipe g , with three-way valve g' , provides a compressed-air supply for use 65 in expelling water from the dome c through the valved pipe f , the branch g^2 leading downwardly therefrom to a permanently-open

water-ballast compartment a' for controlling the contents of the latter. The dome may obviously be filled by opening the water-valve f' and air-valve i , so that the inflowing water may displace the contained air. 70

It will be observed that not only does the admission and expulsion of water to and from the dome serve to vary the buoyancy of the 75 boat, as above described, but the flooding of the dome operates to prevent any undue external water-pressure upon the walls of the relatively fragile dome, the open pipe connection f between the interior and exterior 80 of the same establishing equal internal and external pressures thereon, and thus obviating any danger of collapse during submergence. The trap-door d' obviously offers a 85 safeguard for the occupants in case of the fracture of the dome from concussion due to the explosion of torpedoes in the vicinity of the boat or from any other cause.

To permit the supply of fresh air to the interior of the boat, even while the hull and 90 conning-tower are wholly submerged, but while the dome is still above the surface, the top of the latter is provided with a valve i , fitted to a seat i' and having a stem i^2 with threaded lower end, to which is applied the 95 similarly-threaded hub of a hand-wheel h , adapted when turned in one direction to draw the valve to its seat and when turned in the opposite direction to release the valve and enable it to regain its normally open position 100 by the action of the spring s , interposed upon the valve-stem between a collar i^3 thereon and the bottom of the dome c . The valve i thus constitutes an outwardly or upwardly 105 opening spring-pressed valve which is normally raised from its seat to admit air to the interior of the boat, but is adapted to be automatically closed by external water-pressure when the boat is wholly submerged, so as to prevent the inrush of water through the same. 110 This automatic feature of the air-inlet valve i is designed to be utilized only in cases of emergency wherein sufficient time is lacking for submergence in which to positively seat the valve by the use of the hand-wheel h or 115 when a sea breaks over the dome and at all other times the mechanical closing of the valve is intended to be effected.

While I have in the foregoing description set forth in detail the preferred construction 120 of the several parts of the present improvement, it is to be understood that the various details described may be widely modified without departing from the spirit of the invention. It is obvious that the particular 125 form of the inspection-dome or observation-chamber is wholly immaterial to the transparent and non-reflecting feature of the improvement, so long as the side walls and crown are angularly disposed and in such 130 relation to the hull that each will avoid reflection of light in the direction of an enemy toward which the boat is directed from a source of light. Similarly the particular

type or construction of valves or the specific location described for the air and water pipes leading to and from the said dome or chamber may be varied to suit the different conditions for which the improvement is designed.

Having thus set forth the nature of the invention, what I claim herein, and desire to secure by Letters Patent, is—

10 1. The combination with a submarine boat, of a transparent dome or observation-chamber attached to said boat and projecting outwardly therefrom, and a door or hatch for normally closing and for reestablishing communication between the same and the interior of the boat.

15 2. The combination with a submarine boat, of a transparent dome or observation-chamber surmounting the same, and constructed with conical or flaring side walls and a crown in angular relation therewith.

20 3. The combination with a submarine boat, of a transparent dome or observation-chamber fixed rigidly to the exterior of said boat, a normally closed door for access to said dome from the interior of said boat, and means whereby water may be admitted to and expelled from said dome.

25 4. The combination with a submarine boat, of a dome or observation-chamber fixed rigidly to the exterior of said boat, a normally closed door for access to said dome from the interior of said boat, and means whereby water may be admitted to and expelled from said dome, said dome being so proportioned that when the boat is running awash the filling of the dome will overcome the buoyancy of the boat and cause the latter to descend beneath the surface.

30 5. The combination with a submarine boat, of a transparent dome or observation-chamber fixed rigidly to the exterior of said boat and projecting outwardly therefrom, a normally closed door for access to said dome from the interior of said boat, and a mirror attached to the inner face of said door and adapted to serve as a reflector when upwardly inclined in its open position.

35 6. The combination with a submarine boat, of a transparent dome or observation-chamber secured rigidly to the exterior of said boat and projecting outwardly therefrom, a door for access to said dome from the interior of said boat, an air-outlet valve in said dome, and means applied to said valve for normally maintaining it open but for causing it to close automatically under an exterior water-pressure.

40 7. The combination with a submarine boat, of a transparent dome or observation-chamber secured rigidly to the exterior of said boat

and projecting outwardly therefrom, a door for access to said dome from the interior of said boat, an outwardly-opening spring-pressed air-valve in said dome communicating with the exterior of the same and adapted to close automatically to exclude water from the dome under an external water-pressure.

45 8. The combination with a submarine boat, of a transparent dome or observation-chamber secured rigidly to the exterior of said boat and projecting outwardly therefrom, a door for access to said dome from the interior of said boat, an air-valve in said dome having a stem passing into the interior of the boat, a spring for maintaining said valve normally raised from its seat, and means applied to the valve-stem within the boat for positively pressing the valve to its seat to exclude water from the said dome.

50 9. The combination with a submarine boat, of a transparent dome or observation-chamber upon said boat, a door for access to said dome from the interior of said boat, an air-valve in said dome having a stem entering said boat and screw-threaded upon its inner end, a spring for maintaining said valve normally raised from its seat, and a hand-wheel with internally-threaded hub fitted to the threaded inner end of the valve-stem and adapted to positively draw said valve to its seat to exclude water from said dome.

55 10. The combination, with a submarine boat, of a transparent dome or observation-chamber secured to the exterior of said boat and projecting outwardly therefrom, a door for access to said dome from the interior of said boat, a water inlet and outlet valve for maintaining said dome flooded with water during submergence, and a valved air-supply pipe leading to the interior of said dome from said boat for expulsion of water therefrom.

60 11. The combination with a submarine boat, of a transparent dome or observation-chamber having upwardly and outwardly flaring walls and a crown of different curvature therefrom arranged in angular relation thereto, the same being attached to the said boat and projecting outwardly therefrom.

65 12. The combination with a submarine boat, of a superposed transparent dome or observation-chamber of substantially oval shape with upwardly and outwardly flared side walls and crown joining the same in an angle along the upper edges.

70 Signed at Elizabeth, in the county of Union and State of New Jersey, this 23d day of May, A. D. 1901.
